United States Patent Office

Des. 194,355
Patented Jan. 8, 1963

194,355

PHOTOELECTRIC UNIT

Nathan Verger, Brooklyn, N.Y., assignor to Alarm Device
Manufacturing Co., Inc., a corporation of New York

Filed June 13, 1962, Ser. No. 70,534

Term of patent 14 years

(Cl. D26—1)

FIG. 1

FIG. 2

FIG. 3

FIG. 4

FIG. 5

FIGURE 1 is a perspective view of a photoelectric unit showing my new design;
FIGURE 2 is a front elevational view thereof;
FIGURE 3 is a side elevational view thereof;
FIGURE 4 is a rear elevational view thereof; and
FIGURE 5 is a top plan view thereof.

I claim:

The ornamental design for a photoelectric unit, substantially as shown.
